UNITED STATES PATENT OFFICE

RUSSELL S. KATZ, OF HAMILTON, OHIO

DESIGN FOR A MERCHANTISING OR FLUID DISPENSING STRUCTURE

Application filed June 10, 1932. Serial No. 44,041. Term of patent 14 years.

To all whom it may concern:

Be it known that I, RUSSELL S. KATZ, a citizen of the United States of America, residing at Hamilton, in the county of Butler, State of Ohio, have invented a new, original, and ornamental Design for a Merchandising or Fluid Dispensing Structure, of which the following is a specification, reference being had to the accompanying drawing, forming part thereof.

The figure is a perspective view of a merchandising or fluid dispensing structure, showing my new design. Where the opposite side of the structure is exposed, it is of the same appearance as the side shown.

The merchandising or fluid dispensing structure illustrated in the drawing, which embodies my design, includes a fluid dispensing portion, the sections of which are arranged in a coordinated group between the sections of the article display portion.

I claim:

The ornamental design for a merchandising or fluid dispensing structure, substantially as shown and described.

RUSSELL S. KATZ.
